United States Patent Office.

J. A. LAFLER, OF ALBION, NEW YORK.

Letters Patent No. 80,976, dated August 11, 1868.

IMPROVED BRICK-MACHINE.

The Schedule referred to in these Letters Patent and making part of the same.

TO ALL WHOM IT MAY CONCERN:

Be it known that I, J. A. LAFLER, of Albion, in the county of Orleans, and State of New York, have invented a new and useful Improvement in Brick-Machines; and I do hereby declare that the following is a full, clear, and exact description thereof, which will enable those skilled in the art to make and use the same, reference being had to the accompanying drawings, forming a part of this specification, in which—

Figure 1 is a sectional side elevation of my invention, and

Figure 2 is a front view of the same.

Figure 3 is a detail view, showing my improved method of securing the scrapers and knives to the hollow cast-iron shaft.

Similar letters of reference indicate corresponding parts in all the figures.

This invention relates to certain new and useful improvements on J. A. Lafler's patent brick-machine, No. 37,348, whereby it is made adaptable for making either common or pressed brick, at will, and whereby its general efficiency and usefulness are much increased, as hereinafter set forth.

In the rear side of the press-box A, fig. 1, is a horizontal slot or opening, through which works a slide, B, which is operated by a spur-wheel, C, pinion c, crank D, and connecting-rod d, the spur-wheel C being fixed on the lower end of the grind-shaft E. The object of this slide B is to close the upper side of the press-box A when the mould and clod-crusher F are forced up, so that the clay or mortar cannot return from the press-box to the grind-mill G, when pressure is applied to the said mould and clod-crusher for making pressed bricks. When making common bricks, the slide B is not necessary, and can be thrown out of action by disengaging the connecting-rod d from the crank D. The working of the machine can be changed from common to pressed brick, or *vice versa*, at any time within fifteen minutes.

For operating the swinging frame H by the grinding-power, a short crank-shaft, i I, fig. 2, is placed over the grind-mill, and geared to the main shaft E by gears J. The crank i is loose on its shaft I, but is made to engage with the shaft by means of a clutch-coupling, k, and connection is made between the crank i and the swinging frame H through a connecting-rod and chain, L l, pulley M, windlass-shaft m, and chains n n. The clutch k is so constructed that it will remain engaged only when the crank i is overcoming resistance, and when the crank is lifting the press-frame H the forward motion of the crank is resisted by the weight of said press-frame, but as soon as the crank i has passed its upper dead-point, the connection L l passes to the front of the crank, so that the weight of the press is thrown on the forward side of the crank, and as the weight of the press then pulls forward on the crank, instead of resisting its motion, the coupling k disengages, and the crank falls forward through half a revolution, letting the press-frame drop so that the press is opened immediately, and by this means time is saved in opening the press.

There is a concealed spiral spring in the coupling k, which holds the coupling disengaged until closed by the operator by means of a hand-lever, N, which is done always as soon as an empty mould has been brought under the clod-crusher F.

The bed h, of the swinging frame H, is supported by cams r r, fig. 2, on the shaft R, fig. 1, and these shafts R R are supported by elastic cushions, P P, of rubber. These elastic supports allow a slight yielding of the bed h, when small stone or other obstructions protrude from the mould as it is being drawn out; and the cushions also keep the mould snug up to the clod-crusher, so that they are struck off closely when withdrawn from under the clod-crusher.

I secure the scrapers S and knives s in the hollow cast-iron main shaft E, fig. 1, as follows: A hole or mortise is cast in the shaft for each knife or scraper, and I then form a hook, v, fig. 3, on the tang of each knife or scraper, and after introducing said hook to the inside or chamber of the shaft, it is secured by driving a key, t, behind the tang of the knife, so that the hook v, on the front edge of the tang, engages with the shell of the shaft, as shown, and by this means a very strong and cheap method of securing the knives is obtained.

By combining the slide or throat-closer B and driving-devices with this machine, it gives advantages that

recommend themselves at once to brick-makers, as by this means the machine is capable of making common or pressed bricks; the machine being employed in making common bricks in fair weather, when they can be laid out on the yard to dry, while in wet weather, the machine can be employed in making pressed bricks, as they can be "haked" under shedding as soon as they come from the machine. And in this manner the machine can be kept steadily at work every day, and no losses occur by idleness during wet weather.

Having thus described my invention, what I claim as new, and desire to secure by Letters Patent, is—

1. The self-releasing crank *i*, for operating the swinging press *H*, substantially in the manner and for the purpose set forth.
2. The method of securing the scrapers and knives *S* *s* in the shaft *E*, namely, the hooked tangs *v*, in connection with keys *t* and mortised hollow shaft *E*, substantially as and for the purpose set forth.
3. The combination of the swinging-press frame *H*, telescopic press-box *F* *A*, slide *B*, and driving-devices *d* *D* *c* *C*, working from the foot of the grind-shaft *E*, all constructed and operating in the manner shown and for the purpose described.

The above specification of my invention signed by me, this 8th day of November, 1867.
